BIT BLOCK

Edwin P. Stenger and Armin O. Bruestle, Cincinnati, Ohio, assignors to The Cincinnati Mine Machinery Company, Cincinnati, Ohio, a corporation of Ohio

Application October 10, 1933, Serial No. 692,998

36 Claims. (Cl. 262—33)

This invention relates to mining machinery and is particularly directed to improvements in cutter bits or teeth and holders for mounting the same in coal cutting chains. The present invention also relates to the construction of the chain block or box for a more efficient mounting of the bit and holder relative thereto.

The mining machinery to which these teeth are applied is of that type employing an endless chain. This chain carries the teeth angularly laterally disposed for making a cut through the coal. The angle of mounting of the teeth is varied in transverse planes, whereby the successive teeth make a cut which is sufficiently wide to permit easy passage of the run of chain and the cutter bar through the cut. The present invention being primarily directed to the construction of the teeth or bits and to the mounting thereof, it is only necessary for the purpose of clearly describing and illustrating the same that reference be made to one chain block or link of the cutter chain. Each of these tooth carrying blocks or boxes as they may be termed includes a socket which is transverse to the longitudinal extent of the chain.

The average cutter tooth or bit is subjected to extremely damaging usage and it is constantly necessary to replace the bits. Accordingly, it is an object of this invention to provide an improved bit holder and a device or means for fastening the same in a chain block or box, which elements are conveniently and quickly manipulated by the operator for inserting a new bit or reversing the worn bit, end for end, in cases where a reversible bit is used, thereby reducing bit setting time to a minimum. The ability to quickly set the bit is a distinct time saving advantage since the average miner is required to set hundreds of bits per day.

Because of the variant character of material through which the bits are drawn for the purpose of making a cut, a great many bits are lost. This occurs because of chattering or vibration resulting from pounding, or are sprung from place due to the excessive pressures which develop as they are forced against materials of varying hardness. It is accordingly a further object of this invention to provide an improved bit or tooth mounting, particularly the construction of the holder and box and their relation which appreciably lowers the amount of loss of holders and bits in coal cutting chains, therefore resulting in a great saving or economy in the operation of the mining machine. In other words, a very important feature of improvement is

found in the construction of the holder and its relation to the box, whereby the tendency to lift the holder from its socket or position in the box is materially lessened.

Due to the excessively hard usage to which the bits are subjected, it is of course highly essential that the construction of the holder and the boxes be extremely rugged and durable so that breakage rarely occurs. Therefore, it is a still further object of this invention to provide an improved holder for the bit in which the heavy forces imposed upon the bit in cutting are properly absorbed and counteracted by proper abutment and location of the bit in the holder, and by proper distribution of the mass of the holder. This object may include the provision of replaceable contact elements on the box.

The gauge of the bit, or the distance from the lug to the bit point, in some uses, must be varied according to conditions. Accordingly, it is a further object of this invention to provide a bit mounting or support means which can be interchanged to procure different bit gauge.

In order to accomplish efficient coal cutting, it is also necessary that the bit have ample clearance or projection beyond the line of the holder and the box. It is accordingly a further object of this invention to provide a bit holder and mounting in the box or block which because of the durability of the holder and the manner in which the forces acting on the bit are absorbed within the holder permits ample extension of the cutting point of the bit without overloading the structure of the holder or the box, whereby it does not split or deform, breakage and distortion of the holder being reduced to a minimum. This construction or arrangement results in a good ratio between bit clearance and the length of the bit which is one of the features constantly sought after in this type of apparatus since it has a very important bearing on the cost of bits.

Other objects and further advantages will be more fully apparent from a description of the accompanying drawing, in which:

Figure 1 is a side view of a length of mining machine chain incorporating the improved cutter teeth and mounting therefor.

Figure 2 is a fragmentary end view of a cutter carrying block of the chain.

Figure 3 is a fragmentary sectional view taken on line 3—3, Figure 2, illustrating the bit, bit holder, and block construction in detail.

Figure 4 is a perspective view of one of the replaceable abutment plates of the block.

Figure 5 is a perspective view of the holder and bit assembly.

Figure 6 is a sectional view taken similar to Figure 3, but illustrating a modified form of abutment plate and holder fastening screw arrangement.

Figure 7 is a perspective view of a modified abutment plate of Figure 6.

In view of the fact that the present improvements relate to the structure for mounting the bit and the chain block or box in which the bit is mounted, it has been considered sufficient illustration to show a short length of mining machine chain. The boxes or blocks supporting the teeth are alternate links in the chain. Upon reference to the drawing, the alternately disposed links, commonly known as boxes or blocks, are indicated at 10 and the connecting links of the chain at 11, the links of the chain being held together by means of pins 12 in the usual manner.

Each bit carrying link or box has a lug portion 13 extended from one side thereof. These lugs are cross grooved as at 14 and include sockets 15 extending from the bottom of the groove 14 and into the interior of the link, the transverse angle of the socket being varied as to the successive boxes as desired for the purpose of disposing the teeth at different angles for increasing the width of the cut made by the successively applied teeth.

Each bit or pick holder 16 preferably includes a head 17 and shank 18, the shank insertable into the socket 15 and the head lying in the cross groove 14 of the lug. It will be observed that the chain box or block is constructed so that the holder can be faced in either direction longitudinally of the chain, depending on the direction of drive of the chain. Therefore the construction of the lug may be duplicate as to the respective sides thereof.

Duplicate abutment plates 19 may be mounted at the respective sides of the cross groove. Each plate includes a stud 20 projecting from one face and has a cross groove 21 in its other face including an inclined portion 22 at one end thereof. When the plate is fitted against the side of the groove of the lug the stud 20 fits in a bore 23 extended through the side wall of the lug formed by the cross groove 14. A reinforcing cross rib or bead 24 is provided at the outer or same side of the plate face as the stud and extends along the upper edge thereof. In fixed position of the plate, the plate lower edge engages the bottom of the cross groove, thereby preventing rocking of the plate on the stud and insuring a rigid attachment for the plate.

The holder 16 includes an obliquely disposed opening 25, diamond shaped in the present case for receiving the bit which is cut in this instance from bars of diamond shape cross section. This places the bit in oblique position or forwardly inclined position when the holder is inserted in the lug. The bit has both ends sharpened by obliquely cutting the ends of the diamond shaped length of cutter bit material, the end surfaces 26 appearing from the same side of the bit. The lower portion or heel of the outwardly extended one of these obliquely cut ends is seated in the angular portion 22 of the plate groove 21. The end face 26 of the bit inserted in the holder rests against a cross pin 27 of the holder and the inner end of the bit is held clear of and cannot be damaged by contact with the opposing abutment plate, the pin limiting insertive movement of the bit.

The bits may be described as trapezoidal in side elevation. One of the parallel sides of each bit is considerably shorter than either of the respective oblique end faces thereof. That is to say, the trapezoid has two parallel sides of unequal length. It is preferable that the short side of the bit be of a length not less than one-half the transverse thickness of the bit, that is, the thickness on the minor axis, and not more than one-half the length of either of the respective end faces or surfaces.

Due to the engagement of the bit with the abutment block the bit holder is maintained in a definite position of insertion in the socket. This causes the head of the holder to be cradled in the groove, the shoulder 28 between the head and shank preferably being clear of the bottom of the lug groove. The screw 29 for securing the holder in position in the block is threaded through the bore at a particular side of the lug portion of 20 the block and has a flat dog point which engages an inclined flat surface 30 on the forward face of the holder shank. It is preferable to have the screw disposed angularly downwardly toward the holder with the flat surface 30 of the shank at 25 right angles thereto so that a plane contact is assured and the tendency of the screw is to hold the holder downwardly in its socket. The forward face of the holder shank (see Figure 5) may be described as generally straight with the inclined portion 30 disposed intermediately thereof. A lug or lip 30^a is formed at the lower end thereof.

It will be observed from the foregoing detailed description that bit setting time is reduced to a minimum in the present construction because removal of the bit is accomplished by the simple act of backing off the set screw a fraction of a turn and then moving the holder outwardly in the socket, the outward movement of the holder being limited by the lip 30^a, after which the bit is free 40 to be withdrawn from the holder for the purpose of reversing cutting ends or insertion of a new bit without entirely withdrawing the holder from the lug. Accordingly, reinsertion of the holder in the darkness of the mine is unnecessary which 45 is an important step in efficiency. No time is lost in adjusting the various clamping members as is the case when other than a one-piece holder is used. When it is remembered that a miner is often required to set hundreds of bits a day, it will 50 be realized that savings in bit setting time can appreciably increase the amount of coal cut per mining machine per day.

The loss of holders and bits from coal cutting chains during the cutting operation results in 55 considerable expense, especially when the mounting consists of a number of parts clamped together. Such parts seldom seat or align themselves perfectly and are often jarred loose and lost during the operation of making the cut. In 60 the present construction the loss of bits and holders in service is practically eliminated.

A different type of abutment plate may be utilized (see Figure 7). In this type a small lug 31 is projected from the outer face of the plate and 65 engages in a notch 32 in the lug, the inner face of the plate being grooved on an angle as at 33 for receiving the lower portion of the oblique end of the bit.

It will be seen that the inner end of the bit 70 rests on the pin 27 which absorbs the thrust of the bit resulting from the forces encountered in the cutting operation. Inasmuch as the bit thrust is absorbed within the head of the holder itself, there is no wedging action tending to lift or force

the holder out of the socket. Instead of the bit holder resting on top of the block, it is merely contained in the cross groove with contact at the rear with the adjacent side of the groove of the lug. The holder cannot be forced backwardly because of the support it receives by abutment against the removable abutment plate 19 of the lug.

The engagement of the bit with the abutment plate at an acute angle forms a stop 34 which prevents the bit from moving outwardly or being removed unless the holder is lifted up a slight distance out of the cross groove. The groove in the block not only provides for extremely rigid and secure abutment for the holder and bit but also provides ample space so that the head of the holder can be made more sturdy than would otherwise be the case.

For efficient cutting, it is necessary that the bit have considerable clearance, that is to say, the bit should project a sufficient distance beyond the holder and its mounting for efficient cutting results. However, unless the holder is very sturdy or the bit uneconomically long, the leverage of the projecting bit will cause the forces acting on it to split or deform the holder. As stated above, the recess or cross groove in the block permits the head of the holder to be made of considerable cross section or mass and amply strong and rigid to keep breakage and distortion of the holder to a minimum. As a result of this the life of the holder is unusually long and this combined with the low loss of bits and holders and quick bit setting time makes for economical operation and low cutting costs.

As mentioned above, sufficient bit clearance is readily obtained in this construction with a relatively short bit. This is made possible by the shape of the bit and the manner in which the bit is supported on its inner obliquely cut surface on the cross pin. The bit is so disposed toward the pin and the bit receiving passage that the stresses resulting from the thrust of the bit are not of a localized character and consequently are not as harmful as would otherwise be the case.

Some mining practices necessitate a variable bit gauge, that is to say, it is necessary to vary the distance from the point of the bit or pick to the box. In what is known as long wall mining, the same cut is continued in a long stretch of coal-face. Often in this type of mining the chain carrying bar or jib becomes tilted up or down by the varying nature of the substance being cut. By changing the gauge of certain of the bits, this tilting may be counteracted, since a heavier cut is taken on one side than on the other.

This change of bit gauge is readily accomplished in the present case by a suitable interchange of abutment plates 19. In other words, if an increased bit gauge is desirable, a new seat element in which the seat is higher may be inserted, thereby setting the holder and bit out in the socket.

A higher bit gauge can be obtained with the same abutment plate by placing shims between it and the shoulder against which it bears. It will be noted that shims can also be inserted to compensate for wear which may take place in service at various points where abutment is made, such as on the stop pin in the holder, the rear of the holder head and various other places.

As described heretofore and particularly disclosed in Figure 3, the holder is reversible. This reversibility is provided for the purpose of operating the chain in long wall mining. In long wall

mining the cut is made back and forth along the same long face of coal. This necessitates reversing the direction of chain travel after each cut is made. Accordingly, the present bit mounting is quite adaptable for long wall mining.

If desirable the set screw can be permanently located on one side of the lug and the holder shank can be properly faced on both sides to be engaged by the set screw, (as shown on one side in the drawing), for set screw contact on either side. By the provision of duplicate opposite side faces on the shank the holder is readily reversed and efficiently held without removing and transferring the set screw from one side of the lug to the other.

Referring to Figure 3 or 6 of the drawing, the following advantages of rigidity and secure attachment of the holder are present regardless of the direction in which the bit is directed. The abutment between the plate 19 and the adjacent side of the head of the holder occurs at an equal distance from the point of the bit regardless of whether the set screw is engaging one or the other of the opposite faces of the holder because the engagement or contact of the end face of the holder is the same for either direction. When the holder and bit are placed in the chain lug, the lower portion of the forward end surface of the bit rests against the abutment plate and the rear surface of the head of the holder rests against the chain lug. As the set-screw is moved against the side surface of the shank of the holder, the holder is rotated slightly as the holder shank moves in an arc in the normal clearance of its socket under the influence of the set-screw. This rotating action may be described as a rocking or cam action and takes place on the contacting surfaces of the holder head and the lug. This rotation of the holder rigidly locks the bit in position by increasing its pressure against the abutment plate. This construction is highly advantageous, for with abutment always insured between the rear side of the holder head and the adjacent abutment plate, the stresses imposed on the holder will not be excessive as would be the case when the rear abutment occurs at the point where the set screw makes engagement. The long leverage in the latter instance would cause the holder to become bent or broken.

Having described our invention, we claim:

1. In a mining machine chain, a link including a lug portion, a holder socketed in said lug, said holder including a head portion and said lug including a holder-head receiving recess, an abutment plate removably mounted in said lug adjacent the forward side of said head, a set screw for holding said holder in place, and a cutter bit mounted in the head and projecting angularly therefrom beyond the lug, said bit overlying said removable abutment plate and limiting insertive movement of the holder.

2. A bit carrying box for a mining machine chain including a recess and a socket extended inwardly from said recess, a holder including a head and a shank, the shank engageable in the socket and the head disposed in said recess, said head including a cutter bit receiving opening, a cutter bit mounted in said opening and extended angularly forwardly from the head, and an abutment plate secured against the forward wall of said recess, said cutter bit having an end engaging said abutment plate, said abutment plate having a stud extended from its forward face into said lug and a reinforcing rib on its forward face.

3. A mounting for a bit, comprising, a box in-

cluding a socket, a holder including a head and a shank, said box including a recess for containing said head, the head of said holder having an obliquely disposed bit receiving opening therein, 5 a cross pin disposed through said head across said opening, a reversible bit insertable in said opening having oblique end faces appearing from the same side of the bit, said box including a seating surface adjacent the forward side of the holder-head for seating the outer oblique end face of the inserted cutter bit, the inner end face resting upon said cross pin.

4. A mounting for a coal cutter bit, comprising, a chain lug including a socket, a holder including a head and a shank, said lug including a recess for containing and supporting said head, the head of said holder having an obliquely disposed bit receiving opening therein, a reversible bit insertable in said opening having oblique end faces facing toward the same side of the bit, said lug including a seat in the side of its recess adjacent the forward side of the holder-head for seating the outer oblique end face of the inserted cutter bit.

25 5. In a mining machine chain, a link including a lug portion, a holder socketed in said lug, said holder including a head portion and said lug including a head receiving portion, abutment plates mounted in said lug at the front and rear sides 30 of said head, a set screw for holding said holder in place, and a cutter bit mounted in the head and projecting angularly therefrom, said bit seating in the adjacent one of said abutment plates.

6. In a mining machine chain, a chain link 35 including a lug portion, a holder including a head portion and a shank, said chain link lug including a socket for said shank, said socket including a recess for receiving said head, said head having contact with the rear wall of said recess, means 40 for holding said holder in place, and a cutter bit obliquely mounted in the head and projecting angularly therefrom.

7. A bit carrying lug for a mining machine chain including a socket and a cross groove, a holder including a head and a shank, the shank engageable in the socket and the head disposed in said cross groove, said head including an angularly disposed cutter bit receiving opening, a cutter bit mounted in said opening and extended 50 angularly forwardly from the head, said cutter bit having its outer end resting against the side of the groove for preventing displacement of the bit, and a set screw extended through the lug and engaging the shank of the holder angularly toward the inner end of the socket.

8. A mounting for a coal cutting bit, comprising, a chain link, a holder socketed in said link, said holder including a head portion and said link including a grooved lug portion for containing 60 said head, an abutment plate mounted in said lug at the front side of said groove, means for holding said holder in place, and a cutter bit mounted in the head portion and projecting angularly therefrom beyond the lug, said bit bearing 65 against said abutment plate, whereby said bit is held against removal unless the holder is moved slightly outwardly in its socket.

9. A bit mounting, comprising, a block, a bit, a bit holder mounted in the block including an 70 obliquely disposed bit receiving and supporting socket in its outer end, said socket including a support for the inner end of said bit, means for securing the bit holder in the block, and a removable bit seating plate mounted in the block 75 and providing a rest for the extended outer end

of the bit apart from the support afforded by the holder.

10. A bit mounting apparatus, comprising, a block including a shouldered socket, a bit holder including a head and a shank, said shank insertable in said socket, the rear of said head engaging the rear side of the socket, said head including an obliquely disposed bit socket, a bit mounted in said socket projecting forwardly and angularly, and means on the block for supporting 10 and holding said bit in position.

11. A cutter bit mounting, comprising, a block including a socket, a holder mounted in the socket including a head and a shank, said block including a recess for containing and supporting said head, the head of said holder having an obliquely disposed bit receiving socket therein, a bit insertable in said socket having an oblique end face at its cutting end, said block including a seat in the side of its recess adjacent the forward side 20 of the holder-head forming a rest and abutment for the oblique end face of the bit.

12. In a device of the class described, a bit carrying box including a socket, a holder engageable in said socket, said holder including an obliquely disposed cutter bit receiving opening having a support for the inner end of the bit therein, a cutter bit mounted in said opening against said support and extended angularly forwardly from the holder, said cutter bit having a portion of its 30 forward end face engaging the wall of said socket, and means for securing said holder in place.

13. A mounting for a bit, comprising, a box including a socket, a holder mounted in said socket, said holder having an obliquely disposed bit receiving opening therein, a reversible bit insertable in said opening having oblique end faces appearing from the same side of the bit, said holder including an abutment disposed in said opening supporting the inner end of said bit, said box 40 including a seating surface adjacent the forward side of the holder for seating the outer oblique end face of the inserted cutter bit.

14. In a mining machine chain, a chain link including a lug portion, said lug portion including a socket, a holder mounted in said socket having a bit socket therein including a support for the inner end of the bit, a cutter bit mounted in the socket of the holder against said support and projecting angularly forwardly therefrom, and a 50 clamping device laterally engaging the portion of the holder mounted in the socket of the lug for securing said holder rigidly in position in its socket for binding the bit in its socket by the engagement of the bit with the lug.

15. In a mining machine chain, a chain link including a lug portion, said lug portion including a socket, a holder mounted in said socket and having a bit receiving socket therein including a support for the inner end of the bit, a cutter bit 60 mounted in the socket of the holder against said support and projecting angularly forwardly therefrom, a clamping device laterally engaging the portion of the holder mounted in the socket of the lug for securing said holder rigidly in position in its socket for binding the bit in its socket by the engagement of the bit with the lug, and an abutment for preventing outward movement of said bit.

16. In a device of the class described, a block 70 including a socket, a bit holder engaged in said socket and having a bit receiving socket therein including a support for the inner end of the bit, a bit mounted in said bit receiving socket against said support thereof and projecting angularly 75

therefrom beyond the adjacent wall of the socket, a set screw in the block engaging one side of said holder, said holder including an inclined portion on its side engaged by the set screw, whereby said set screw retains the holder in the socket and engages the outer end of the bit against the block.

17. A bit carrying block for mining machine chain, comprising, a block including a socket, a bit holder secured in said socket including a bit receiving socket, a bit mounted in the bit receiving socket of said holder and projecting angularly forwardly from the holder, said bit extended within the socket of the block in position of use and having an end face engaging the block, the inner end of said holder including a lip, a set screw in the block engaging the side of the holder above the lip and adapted to be engaged by the lip as the holder is withdrawn, said lip and set screw spaced apart a distance sufficient for permitting outward withdrawal movement of the holder for clearing the bit from engagement with the block.

18. In a mining machine chain, a lug including a socket, a holder mounted in the socket of said lug having a bit receiving socket therein, a bit removably mounted in the bit receiving socket of said holder and projecting angularly forwardly from the extended end thereof, and a set screw in said lug adapted to engage the adjacent side of the holder, said bit having an oblique end face engaging the lug, the extreme upper portion of the rear side of the holder head engaging the lug, said set screw inclined downwardly inwardly in the lug for moving the holder in an arc in the socket and causing more positive engagement of the oblique end face of the bit with the lug.

19. A bit carrying lug for a mining machine chain, including a socket, a holder mounted in said socket, said holder including a cutter bit receiving opening including a support for the inner end of the cutter bit, a cutter bit mounted in said opening against said support and extended angularly forwardly from the holder, and an abutment plate secured against the forward wall of said socket, said cutter bit having its extended outer end in engagement with said abutment plate.

20. In a mining machine chain, a link including a lug portion, said lug portion including a socket, a holder mounted in said socket including a bit receiving socket having a support for the inner end of the bit therein, an abutment plate removably mounted in said lug adjacent the forward side of the outer end of said holder, a set screw for securing said holder in position in said socket, a cutter bit mounted within the bit receiving socket of the holder and against the support therein and projecting angularly therefrom beyond the lug, said bit engaged against said removable abutment plate, and means for securing said abutment plate in position, whereby said abutment plate is maintained against displacement when said holder is in position in the socket of said lug.

21. A bit carrying lug for a mining machine chain, including a socket, a holder mounted in said socket, said holder including a cutter bit receiving opening, a cutter bit mounted in said opening and extended angularly forwardly from the holder, an abutment plate secured against the forward wall of said socket, said cutter bit having its extended outer end in engagement with said abutment plate, said abutment plate having a stud extended from its forward face into said lug, and

means on said lug engaged by said abutment plate for preventing rotation thereof on said stud.

22. In a mining machine chain, a lug including a socket, a holder mounted in the socket of said lug, a bit removably mounted in said holder projecting angularly forwardly from the extended end thereof, and a set screw in said lug adapted to engage the adjacent side of the holder, said bit having an oblique end face engaging the lug, the extreme upper portion of the rear side of the holder head engaging the lug, said set screw maintaining the holder head and the bit in contact with the lug.

23. In a mining machine chain, a lug including a socket, a holder mounted on said lug and including a shank disposed in said socket, a bit having its inner end supported in said holder and projecting angularly forwardly in contact with the lug, and a set screw in said lug inclined downwardly inwardly in the lug for forcing the shank of said bit laterally in said socket.

24. A mounting for a bit, comprising, a box including a socket, a holder mounted in said socket, said holder having an obliquely disposed bit receiving opening therein, a reversible bit insertable in said opening having oblique end faces appearing from the same side of the bit, said holder including an abutment disposed in said opening supporting the inner end of said bit, said box including a seating surface adjacent the forward side of the holder for seating the outer oblique end face of the inserted cutter bit, and means for retaining the holder in its socket for clamping the bit between the holder and the seating surface.

25. In combination with a bit holding lug of a mining machine chain, a bit holder engaging within a socket in the chain lug, a bit having one end thereof socketed and seated within the head of said holder and an opposite cutter end protruding therefrom, the protruding end of the bit surfaced for engaging with the lug compressing the bit within the holder socket and clamping the same between the holder and lug upon urging the holder into the lug socket, and screw means cooperating with the holder for securing the same in the lug socket.

26. A bit carrying device for use in a cutter chain, comprising, a box having a socket therein, a holder element mounted in said socket, said element including an obliquely disposed cutter bit receiving bore therein, a cutter bit mounted in said opening in position with a cutting end thereof extended angularly forwardly beyond the holder element, said cutter bit having the aforesaid cutting end resting on the box at the forward side wall of the socket in the box, said holder element having the extreme upper portion of its rear surface engaging the rear surface of the socket in the box, and means for securing said holder in position.

27. A mounting for a cutter bit, comprising, a block having a socket therein, a bit holder mounted in said socket, said holder including a forwardly inclined bit receiving passage, a cutter bit mounted in said passage and extending angularly forwardly from the holder, said cutter bit having a portion of its forward end engaging the block at the forward side wall of said socket in the block, means within the holder for limiting insertive movement in said bit, and means for securing said holder in position.

28. In a cutter chain, a bit block having a socket, a holder mounted in said socket including an

angularly disposed socket therein, a cutter bit having obliquely extended end faces providing cutting points, said cutter bit mounted in said socket of said holder, said block including a portion extended outwardly, and a removable abutment plate in said portion of the block and having an inclined surface engaged by the outer end face of the bit opposite to the point thereof, said contact of the abutment plate and cutter bit providing the only contact of the cutter bit apart from the holder.

29. In a cutter chain, a bit block having a lug portion, said lug portion having a socket therein, and extensions projected upwardly from the lug 15 at the front and rear of said socket.

30. In a cutter chain, a bit block having a lug portion, said lug portion having a socket therein, extensions projected upwardly from the lug at the front and rear of said socket, and an abutment 20 plate secured in one of said extensions against its inner face.

31. A reversible coal cutting bit formed from bar stock having cutting ends presenting flat opposingly obliquely disposed surfaces providing cutting points at the same side of the bit, said bit of trapezoidal form in side elevation, the short side of which is of a length not less than one-half the transverse thickness of the bar stock and not more than one-half the length of either of the respective 25 end surfaces.

32. A reversible coal cutting tooth diamond shaped in cross-section having obliquely disposed end surfaces appearing from the same side of the tooth and providing cutting points located at the 35 same longitudinal side edge of the tooth, said tooth of trapezoidal form in side elevation, the short side thereof being of a length not less than one-half the transverse thickness of the tooth and not more than one-half the length of either of the respective obliquely disposed end surfaces thereof.

40. 33. In a cutter chain, a chain lug including a socket, a bit holder mounted in said socket, said bit holder having an angularly disposed socket

therein, a bit mounted in said socket of said holder, said bit of trapezoidal outline in side elevation and having a short side of a length not less than one-half the transverse thickness of the bit and not more than one-half the length of either of its respective end surfaces, the outer end surface of the bit resting on the chain lug, and means for securing the holder in the chain lug.

34. A cutter bit adapted to be mounted in a coal cutter chain, the cross section of said bit having 10 a major and minor axis and symmetrical on these axes, said bit of trapezoidal outline in side elevation, one parallel side of said trapezoid being of a length not less than one-half the thickness of the bit on its minor axis and not more than one- 15 half the length of either of the remaining sides, the obliquely disposed end surfaces forming a cutting point at each end of the bit at the same side thereof.

35. In a cutter chain, a chain lug, a bit holder 20 having a head and a shank, said shank socketed in said chain lug, and said head having its rear surface engaged against the chain lug, a bit angularly mounted in the holder head and projecting forwardly therefrom with its active cutting end 25 surface engaging the lug, and means engaging the shank of the holder causing the holder to rock on the lug on the rear contacting surface thereof for clamping the forward end surface of the bit 30 against the lug.

36. A reversible cutter bit formed from diamond shaped bar stock, providing obliquely disposed end surfaces appearing from the same side of the bit and a cutting point located at each end of the same longitudinal side edge thereof, said bit having a short longitudinal side edge disposed opposite to said first mentioned longitudinal side edge, said latter edge being of a length not less than one-half the thickness of the bit on its minor axis and not more than one-half the length of either 40 of the respective end surfaces of the bit.
